UNITED STATES PATENT OFFICE.

JOHN WOLDEMAR RUBEN, OF PORTLAND, OREGON.

CAR-WINDOW CLEANER.

1,081,000.

Specification of Letters Patent.

Patented Dec. 9, 1913.

Application filed January 24, 1912. Serial No. 673,159.

To all whom it may concern:

Be it known that I, JOHN W. RUBEN, a citizen of the United States, residing at Portland, in the county of Multnomah, State 5 of Oregon, have invented certain new and useful Improvements in Car-Window Cleaners; and I do hereby declare the following to be a full, clear, and exact description of the invention, such as will enable others 10 skilled in the art to which it appertains to make and use the same.

This invention relates to window cleaners and more especially to a device adapted for use in connection with railway cars and 15 the like for readily cleaning water, snow or dust from the window pane without the necessity of the motorman getting out of the car.

Another object of the invention is to provide 20 an improved window cleaning device which is adapted to be secured to the outside front wall of the car in a stationary position and adapted for cleaning the window pane by moving the window vertically.

With the above and other objects in view, 25 the invention consists of certain combinations and arrangements of parts, as will be hereinafter more fully described and claimed, it being a still further object of 30 the invention to provide a device which will not be likely to get out of working order.

In the drawings:—Figure 1 is a front elevation of a fragmentary portion of a car and more especially the front wall thereof 35 with my improved window cleaner secured thereto and with the window in a closed position. Fig. 2 is a vertical sectional view of the device taken on the line 2—2 of Fig. 1. Fig. 3 is a view similar to Fig. 1 but 40 showing the window lowered for purposes of cleaning the same as the window descends. Fig. 4 is a side elevation of the cleaner enlarged. Fig. 5 is a cross sectional view on the line 5—5 of Fig. 1.

Referring to the drawings in detail, there is shown a front wall 10 of a car body between the usual center window frame 11 of which a window 12 is vertically slidable, the same carrying a pane 13 although said window 45 frame may be of any suitable form providing that it is movable vertically. The window frame 12 and pane carried thereby are adapted to be lowered in order to open the window, this structure being used for pur-

poses of illustration, in which position the 55 said parts will lie adjacent the lower front wall of the car body and in order to thoroughly clean the same of water, snow or dust which may have collected upon the pane, I provide my improved device. 60

As shown in the drawings, my improved cleaner comprises a pair of bars or brackets 14 which are secured vertically on the outside wall of the car beneath the window and in spaced parallel relation, each of said bars 65 being provided with upper and lower transverse slots 15 therethrough and with an enlarged intermediate slot 16. A second or inside bar 17 is disposed in contact with the inner face of each of the bars 14 and rotatably receives the end portions of an upper shaft 18 carrying a brush roller 19 to rotate therewith while the extreme ends of said shaft extend through the upper slots 15 and are adapted for transverse movement therein. 70 A lower shaft 20 has its end portions similarly mounted in the lower slots and also journaled in the inside bars 17, the said shaft 20 carrying a roller 21 provided with a sponge covering or the like for thoroughly 75 absorbing the matter scraped from the pane or loosened by the brush roller 19, the bristles of which are comparatively coarse.

Connecting the inside bars 17 centrally of their lengths is a cross bar 22 disposed with 80 one flat face toward the front of the car and having a leaf spring 23 secured centrally of its inside face and with its end portions 24 extending in an angular direction to contact with the front wall of the 85 car to force the cross bar 22 away from the front wall of the car and thereby hold the brush roller 19 and the sponge roller 21 in positive contact with the window pane for 90 thoroughly cleansing the same. The end 95 portions of the cross bar 22 are horizontally movable in transverse slots 16 in the outside bars 14 so as to compensate for wear and insure proper contact of the rollers with the pane. A gear wheel 25 is secured 100 to one extremity of the shaft 18 and is adapted to mesh with a larger gear wheel 26 carried by the corresponding end of the shaft 20, said latter gear being approximately twice the diameter of the first named 105 gear to impart increased velocity of rotation to the brush roller. In order to rotate said rollers, the lower shaft 20 carries at one

end a spool or drum 27 around which a flexible cord or cable 28 is wound and engaged around a pulley 29 adjacent the upper ends of the bars and connected to the adjacent 5 lower corner of the window frame as shown, said flexible cable or connection being of a length equal to the height of the window plus the distance from the lower roller or spool 27 to the point of attachment of the 10 cable to the window. A spool or drum 30 is secured to the opposite end of the shaft 20 relative to the spool 27 and between the ends of the roller 21 and the inside bar 17 as shown, said spool 30 having a flexible cable 15 or connection 31 secured thereto and passed around a pulley 32 secured to the front wall of the car therebeneath and then extended upwardly and connected to the lower wall of the window frame opposite to the point 20 of connection of the cable 28, said cable 31 being of a length equal to twice the height of the window plus the distance between the spool 30 and the point of attachment thereof to the window frame 12. It will thus be 25 seen that since the cables are wound in opposite directions upon the respective spools or drums movement of the window downwardly will unwind the cable 28 from the drum 27 and impart opposite rotation to the 30 cleaning rollers through the intermeshed gears and thus wind the cable 31 on the drum 30 whereby when the window is moved upwardly or moved in a reverse direction, the reverse operation will take place.

I claim:—

1. In a cleaner for slideable windows, a plurality of cleaner rollers rotatably supported, intergeared connections between the rollers, said rollers being adapted for transverse movement toward and away from a window to be cleaned and means carried by the roller supports for resiliently holding the rollers in contact with the window.
2. In a cleaner for slideable windows, spaced vertical supports adapted for connection to a wall and having transverse slots therethrough, upper and lower rollers having their end portions engaged in said slots, cleaning elements upon the said rollers, inside supports intimately adjacent the aforementioned vertical supports, a brace between the said inside supports, a spring member carried by said brace and adapted to contact with said wall when the device is in position, an operative connection between the rollers, and oppositely wound cables upon the end portions of the lower roller adapted for connection to a window frame, whereby shifting of the frame will cause said rollers to be driven in opposite directions.

In testimony whereof, I affix my signature, in presence of two witnesses.

JOHN WOLDEMAR RUBEN.
